TOILET VENTILATING SYSTEM

Edward W. Sowards, Campbell, Calif.

(Rte. 1, Box 785, Love Creek Road, Ben Lomond, Calif.)

Filed Apr. 13, 1959, Ser. No. 895,787

4 Claims. (Cl. 4—213)

This invention relates in general to new and useful improvements in ventilators, and more specifically to an improved ventilator for a toilet pressure flush valve.

Numerous attempts have been made to deodorize toilets of the type having pressure flush valves. However, heretofore all of the ventilators have been of an extremely bulky type and therefore not suitable. One of the main problems encountered is providing a suitable vent take-off which may be connected to the toilet bowl for venting the toilet bowl and at the same time be in an out-of-the-way position at all times.

It is therefore the primary object of this invention to provide a ventilator for a toilet bowl which has connected thereto a pressure flush valve, the ventilator including a vent line which is connected to the water supply or flush pipe extending between the flush valve and the toilet bowl whereby except when the toilet bowl is being flushed, the toilet bowl is vented through the water supply pipe.

Another object of this invention is to provide an improved ventilator for toilet bowls of the type having pressure flush valves, the ventilator including a vent line extending from the water supply pipe for the toilet bowl and being connected to the sewer pipe for the toilet bowl, the connection being of such a nature that only vented air is passed through the vent line.

Another object of the invention is to provide an improved fitting which may be mounted intermediate a toilet bowl and a sewer pipe whereby vented air from the toilet bowl may be forced into the sewer pipe.

A further object of the invention is to provide an improved ventilator for a toilet bowl of the type having a pressure flush valve, the ventilator including a vent line which is connected to the water supply pipe which extends between the pressure flush valve and the toilet bowl, the vent line including a ball check valve which prevents the passage of water through the vent line during a flushing operation.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a side elevational view of a conventional type of pressure flush valve type of toilet and shows connected thereto the ventilator which is the subject of this invention;

FIGURE 2 is a plan view of the toilet of FIGURE 1 and shows further the arrangement of components of the ventilator, a portion of the seat of the toilet bowl being broken away and showing the position of a sealing gasket between the seat and the toilet bowl;

FIGURE 3 is an enlarged fragmentary sectional view taken through the connection between the vent line of the ventilator and the water supply pipe for the toilet bowl and shows the details of the check valve thereof;

FIGURE 4 is an enlarged fragmentary sectional view taken substantially upon the plane indicated by the section line 4—4 of FIGURE 1 and shows the specific details of a vent fitting disposed intermediate the toilet bowl and a sewer pipe for facilitating the entrance of vent gases into the sewer pipe; and

FIGURE 5 is an enlarged fragmentary sectional view taken substantially upon the plane indicated by the sec-

2

tion line 5—5 of FIGURE 1 and shows the manner in which a support for a pivotally mounted switch actuator is secured to one of the hinge brackets for the toilet seat.

Referring now to the drawings in detail, it will be seen that there is illustrated a conventional type of toilet assembly which is referred to in general by the reference numeral 10. The toilet assembly 10 includes a customary toilet bowl 12 which is seated upon a floor 14. Extending upwardly through the floor 14 is a sewer or waste pipe 16 to which the toilet bowl 12 is normally connected. The toilet bowl 12 also carries the conventional seat 18 which is connected to the toilet bowl 12 by means of a hinging assembly 20.

The room in which the toilet 10 is mounted also includes a wall 22. A pressurized water line 24 extends from the wall 22 and is connected to a conventional pressure flush valve 26. A water supply or flush pipe 28 extends between the pressure flush valve 26 and the toilet bowl 12 for supplying water to the toilet bowl 12 to flush the toilet bowl 12 when the valve 26 is actuated.

The ventilator, which is the subject of this invention, is referred to in general by the reference numeral 30. The ventilator 30 includes a special vent fitting 32 which is disposed between the base of the toilet bowl 12 and the sewer pipe 16. The vent fitting 32 includes a member having an annular portion or ring 34 which is of generally U-shaped or a C-shaped cross-section and which has integrally connected thereto a flat tube portion 36. Seated on the annular portion 34 is an annular flange 36' of a funnel-shaped member 38 which also forms part of the vent fitting 32. The discharge or outlet pipe 40 of the toilet bowl 12 is received in the funnel 38 and forms a seal therewith. On the other hand, the annular portion 34 forms a seal with the upper end of the sewer pipe 16. Thus the necessary seal is maintained between the toilet bowl 12 and the sewer pipe 16 and at the same time vented air may be forced down into the sewer pipe 16 through the vent fitting 32.

A vent pipe comprising a section 42 is connected to the tube 36. The tube 36 is provided with a bore therethrough and the vent pipe section 42 is secured to the opposite surfaces of the tube 36 in sealed relation by means of flanges 44 and 46 which have fasteners 48 extending therethrough. In this manner the member of which the tube 36 is a part may be turned over so that the tube 36 may extend in an opposite direction from that illustrated in FIGURE 2. Incidentally, while the tube 36 has been illustrated as overlying the floor 14, in new installations the tube 36 may be buried in the floor 14.

The vent pipe section 42 has a slip connection 50 with a vent pipe section 52. The vent pipe section 52 is connected to an outlet of a suction fan or blower 54 which has an electric motor 56. Operation of the electric motor 56 is controlled by means of a switch 58, the operation of which will be described in more detail hereinafter.

Another vent pipe section 60 is connected to the blower 54 in sealed relation by means of a flange 62. It is to be understood that the vent pipe section 60 will extend into the blower 54 and will be provided with a check valve to prevent back flow of air.

Still another vent pipe section 64 is connected to the vent pipe section 60 by means of a slip joint 65'. The vent pipe section 64 is threadedly connected to an upper portion of a ball check valve which is referred to in general by the reference numeral 66.

As is best shown in FIGURE 3, the ball check valve 66 includes a sectional hollow sphere or housing 68 which is formed of an upper half 70 and a lower half 72. The two half-sections 70 and 72 are clamped together by means of a split ring 74 and are sealed relative to each other by means of a sealing gasket 76. The lower hous-

ing half 72 has a pipe section 78 which is secured to and opens into the water supply pipe 28.

The upper portion of the upper housing half 70 is configured to form a valve seat 80. A concavo-convex foraminous cage or wire retainer 82 is carried by the sealing gasket 76 and is clamped between the sealing gasket 76 and the housing halves 70 and 72. A buoyant ball check valve member 84 is supported by the wire retainer 82 and normally is spaced from the seat 80. However, should water from the pipe 28 enter the check valve 66, the ball valve member 84 will float to its dotted line position into engagement with the seat 80 and prevent the passage of water up through the vent pipe section 64.

The hinge assembly 20 includes a pair of mounting brackets 86. Each of the mounting brackets 86 includes a shaft portion, such as the shaft portion 88 illustrated in FIGURE 5. Releasably secured to one of the shaft portions 88 is a support bracket generally referred to by the numeral 90. The support bracket 90 includes an elongated arm 92 which is provided at one end thereof with a clamp assembly 94 which is secured to the shaft 88. Pivotally connected to the opposite end of the arm 92 is a lever 96 which extends between the switch 58 and the toilet seat 18. The switch 58 is actuated by the lever 96 by the weight of a person seated on the toilet seat 18.

At this time it is pointed out that secured to the underside of the toilet seat 18 is an elongated sealing gasket 98. The sealing gasket 98 is compressible and when a person is seated upon the toilet seat 18, a seal is formed between the toilet seat 18 and the toilet bowl 12 to prevent the escape of undesired gases.

In the operation of the toilet ventilator 30, when a person is seated on the toilet seat 18, the weight of the person will result in the depression of the toilet seat 18 sufficiently to pivot the lever 96 and actuate the switch 58. The actuation of the switch 58 will result in the energization of the electric motor 56 and the operation of the blower 54. The blower 54 will produce a suction within the toilet bowl 12 and draw vent gases back up through the water supply pipe 28, through the check valve 66 and through the vent pipe sections 60 and 64. The gases will then be forced downwardly through the vent pipe sections 42 and 52 into the tube 36 of the vent fitting 32. The gases will be forced out of the vent fitting 32 down into the sewer pipe 16. Should the toilet 10 be flushed while the blower 54 is operating, water under pressure in the water supply pipe 28 will, of course, enter the check valve 66. The water will begin to flood the housing 68 of the check valve 66 with the result that the ball valve member 84 will float up and engage the seat 80 to prevent the flow of water into the vent pipe section 64. As a result, the venting operation will be momentarily discontinued until the flushing operation is over. At that time, the ball valve member 84 will drop to its solid line position of FIGURE 3 and vented air will then be pulled through the check valve 66.

From the foregoing disclosure of the invention, it will be readily apparent that the toilet ventilator 30 may be readily incorporated in either existing installations or in new installations with a minimum of modifications. It is merely necessary to unseat the toilet bowl 12 and to place the vent fitting 32 between the toilet bowl 12 and the sewer pipe 16. Then it is necessary to modify the water supply pipe 28 so as to connect the check valve 66 thereto. The remainder of the toilet ventilator 30 may then be connected to the toilet 10 without modification thereto.

From the foregoing, the construction and operation of the device will be readily understood and further explanation is believed to be unnecessary. However, since numerous modifications and changes will readily occur to those skilled in the art, it is not desired to limit the invention to the exact construction shown and described,

and accordingly all suitable modifications and equivalents may be resorted to, falling within the scope of the invention as claimed.

What is claimed as new is as follows:

- 5 1. A ventilating system for toilets of the type including a bowl having a flush pipe connected thereto and a waste pipe communicating therewith, said system comprising a vent pipe connected to the flush and waste pipes, a suction fan interposed in the vent pipe for drawing air thereinto from the bowl through the flush pipe, and a check valve interposed in the vent pipe for preventing the passage of water from the flush pipe, said check valve including a hollow sphere comprising complementary upper and lower half-sections, said upper section having an opening in its upper portion communicating with the vent pipe, said lower section having an opening in its lower portion communicating with the flush pipe, said upper section including a valve seat adjacent the opening therein, a circular, generally concavo-convex, foraminous cage mounted horizontally in the sphere, a buoyant ball operable in the cage and engageable with the seat for closing the vent pipe, and means for detachably securing the half-sections together and for securing the cage in position in the sphere.

2. A ventilating system for toilets of the type including a bowl having a flush pipe connected thereto and a waste pipe communicating therewith, said system comprising a vent pipe connected to the flush and waste pipes, a suction fan interposed in the vent pipe for drawing air thereinto from the bowl through the flush pipe, and a check valve interposed in the vent pipe for preventing the passage of water from the flush pipe, said check valve including a hollow sphere comprising complementary upper and lower half-sections, said upper section having an opening in its upper portion communicating with the vent pipe, said lower section having an opening in its lower portion communicating with the flush pipe, said upper section including a valve seat adjacent the opening therein, a circular, generally concavo-convex, foraminous cage mounted horizontally in the sphere, a buoyant ball operable in the cage and engageable with the seat for closing the vent pipe, and means for detachably securing the half-sections together and for securing the cage in position in the sphere, said cage having its peripheral portion engaged between the half-sections, said means comprising a split ring encircling the half-sections at the juncture thereof for clamping said half-sections together with the cage therebetween.
3. In combination, a toilet comprising a bowl, a flush pipe connected to said bowl and a vertical waste pipe beneath the bowl, said bowl including an outlet pipe extending downwardly into the waste pipe in spaced, concentric relation thereto, and a ventilator comprising a vent pipe having one end connected to the flush pipe, a suction fan interposed in the vent pipe for drawing air thereinto from the bowl through the flush pipe, and means connecting the other end of the vent pipe to the waste pipe for discharging the air thereinto, said means comprising a fixture between the waste pipe and the bowl, said fixture including a horizontal inwardly opening ring of generally U-shaped cross-section mounted coaxially on the upper end of the waste pipe and communicating therewith, a generally frusto-conical funnel mounted centrally in the ring and seatingly receiving the lower end of the outlet pipe, and a tube communicating with the ring and extending tangentially from the periphery thereof and connected to the vent pipe.
4. In combination, a toilet comprising a bowl, a flush pipe connected to said bowl and a vertical waste pipe beneath the bowl, said bowl including an outlet pipe extending downwardly into the waste pipe in spaced, concentric relation thereto, and a ventilator comprising a vent pipe having one end connected to the flush pipe, a suction fan interposed in the vent pipe for drawing air thereinto from the bowl through the flush pipe, and means connecting

the other end of the vent pipe to the waste pipe for discharging the air thereinto, said means comprising a fixture between the waste pipe and the bowl, said fixture including a horizontal inwardly opening ring of generally U-shaped cross-section mounted coaxially on the upper end of the waste pipe and communicating therewith, a generally frusto-conical funnel mounted centrally in the ring and seatingly receiving the lower end of the outlet pipe, and a tube communicating with the ring and extending tangentially from the periphery thereof and connected to the vent pipe, said funnel including an external supporting flange on its upper end resting on the upper portion of the ring, said funnel extending downwardly through the

lower portion of the ring and into the waste pipe in spaced, concentric relation thereto.
